UNITED STATES PATENT OFFICE.

HERBERT LLOYD WILLIAMS, OF AKRON, OHIO, ASSIGNOR TO THE WILLIAMS FOUNDRY & MACHINE COMPANY, OF AKRON, OHIO, A CORPORATION OF OHIO.

VULCANIZER HEAD.

Application filed March 6, 1924. Serial No. 697,238.

The present invention, relating, as indicated, to quick-opening heads for horizontal vulcanizers, is more particularly directed to an improved head for use on horizontal vulcanizers in which the head is supported on a movable carriage, allowing it to be first unlocked or released from the vulcanizers and then moved out of the plane of the end of the vulcanizer, after which the carriage is moved transversely to bring the head out of alignment with the end of the vulcanizer to permit free access to the interior thereof. The heads of horizontal vulcanizers are extremely heavy and must be very strongly supported to maintain them in locking registration with the end of the vulcanizer proper, and the present invention is directed to an improved means for supporting the head for such purposes. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

30 In said annexed drawings:—

Fig. 1 is a side elevation showing my improved vulcanizer head; Fig. 2 is also a side elevation showing the means for adjusting the vertical position of said head on its supports; Fig. 3 is a plan view of said head; Fig. 4 is a front elevation of the vulcanizer and head in position thereon; Fig. 5 is also a front elevation showing the vulcanizer and head of a slightly modified construction; Fig. 6 is a plan view of the head shown in Fig. 5; Fig. 7 is a side elevation of the head of Figs. 5 and 6; Fig. 8 is a view of an improved packing gland for use in sealing the head of the vulcanizer; and Fig. 9 is a side elevation 45 of a modification of the construction shown in Fig. 2.

Referring now to Figs. 1, 2, 3 and 4, there is shown a horizontal cylindrical vulcanizer 1 provided with a flange 2 encircling its outer open end, which is adapted to receive a circular concave head or end member 3. The flange 2 is provided with a series of spaced lugs 4, beneath which are adapted to engage corresponding lugs 5 formed around the peri-

phery of the cover 3, the engagement being effected by a partial rotation of the cover after it has been pressed inwardly with the lugs 5 between the lugs 4. The lugs are so formed on their engaging surfaces that the head 3 is pressed into the vulcanizer during this engagement, and is securely and frictionally engaged against the inner face of the flanged ring surrounding the open end of the vulcanizer. This locking construction is commonly used in horizontal vulcanizers and need not be explained in greater detail.

The head 3 is of very considerable weight, particularly when made in sizes for the larger types of vulcanizers, and must be securely supported in such a way as to be freely movable, both into and out of engagement with the flanged ring on the vulcanizer, and also out of position in front of the vulcanizer so that free access may be had to the interior for the placing and removal of the rubber goods to be vulcanized. I mount the vulcanizer head on a supporting arm 6, secured to a bracket 7 provided with spaced arms 8 and 9, which are apertured and engage over a shaft 10. The shaft 10 is adjustably supported in a second bracket, consisting of spaced horizontal arms 11 and 12 connected by a brace 13, and having spaced ends 14 and 15, through which passes a shaft 16 adjustably mounted, as to its vertical position, in a carriage 17, which is best seen in Fig. 4. This carriage is provided with supporting rollers or wheels 18 and 19 at its bottom, and with a guide roll or wheel at its top. The wheels 18 and 19 rest upon a rail or track 21 and the roller 20 travels in a channel 22 secured to a series of brackets 23, which are suitably mounted to the wall in which the press 1 is mounted.

35 The cover 3 is secured to the arm 6 by means of a trunnion 25 passing through the bracket and arm, and has a slight oscillatory movement with respect to the arm 6, depending upon how tightly the trunnion 25 is drawn up. Vertically above the arm 6 there is secured to the cover an angle plate 27 having a vertical surface 28 adapted to engage against a second plate 29 secured to the bracket 7. The vertical position of the cover 3 is determined by the engagement between these two plates 28 and 29, and may be slightly varied by means of a bolt 30 passing through an extension 31 of the bracket 7, and

bearing against the plate 27. By adjusting this bolt the cover may be tilted slightly either toward or away from the vertical position, and in such a way as to bring it into 5 parallelism with the flanged ring 2 on the end of the vulcanizer press 1.

In Fig. 9 I have shown a modification of the supporting or adjusting means for the cover of Fig. 2, in which form a support 90 10 is mounted on the lower portion of the cover and bears against an extension 91 of the arms 7, there being adjusting screws 92 for slightly varying the vertical position of the cover with respect to the arm and extension in the 15 same manner as the adjustment described in Fig. 2.

The cover may be locked either in its open or closed position by means of a notched arm 33 provided with recesses or notches 34 and 20 35. By lifting the member 33 the cover may be swung to the desired position, either locked or unlocked, when the arm is swung downward, causing one of the notches 34 or 25 35 to engage over a rib 36 formed on the top of the extension 28 of the bracket 7.

The bracket 7 is secured at the desired height on the shaft 10 by means of bolts 38 and 39 passing through the arms 8 and 9 on the bracket and engaging against this 30 shaft, while the vertical position of the shaft may be adjusted and fixed by means of an adjusting bolt or screw 40 passing through the lower arm 12, and bearing against the lower end of this shaft 10. In the manner 35 described the position of the cover, that is both its vertical height and the plane in which it stands, may be completely adjusted to bring the cover into perfect parallelism and 40 registration with the flanged locking ring on the press.

The second bracket is similarly adjustably secured to the shaft 16 by means of adjusting screws 41 and 42, and the position of this shaft is adjusted and fixed by means of an 45 adjusting screw 43 engaging against the lower end of this shaft.

In operation, the cover, if in locked position, is removed from the press 1, first lifting the locking member 33, then rotating the 50 cover out of engagement with the lugs on the flanged ring, this movement being conveniently executed by inserting a bar in one of the two angle members 45 mounted opposite each other adjacent the outer edge of the 55 cover, after which the cover is swung away from the front of the press a short distance.

The carriage 17 is then pushed to the side of the vulcanizer members, the door being carried bodily out of position in front of the 60 press and allowing complete and free access to the interior. It will be understood that ordinarily a battery of presses are employed, mounted parallel to each other with their ends in the same plane, and the tracks 21 and 65 22 may extend along the front of the entire

battery of presses and serve to support the carriages, on which all of the doors of the various presses are carried.

In Figs. 5, 6 and 7 I have shown a modified construction in which the carriage consists of a bowed frame 50 provided with a vertical support 51 thereon, the wheels 52 for the carriage being mounted in the lower part of the spaced legs 50, while the upper or guide wheel 52 is mounted on the upper 70 end of the member 51. In this construction the cover 53 is carried on the end of a threaded shaft 54, passing through a suitably formed boss 55 on the vertical member 51 and operated by means of a hand wheel 56. 75 By turning the wheel 56 the shaft 54 operates to advance the cover 53 toward the flanged ring on the end of the press or to move it away from the same, and after the cover has been moved out of the plane of the ring on the end of the press the carriage may be shifted transversely to displace the cover from in front of the vulcanizer. 80

The same means for locking the cover to the press are here employed, but the vertical position of the carriage and of the cover are secured by adjusting screws 57 engaging against the axles on which the lower wheels 52 are carried, and by other screws 59 engaging against opposite sides of the axle, on which the guide roll 52 is carried. By adjusting these various screws the vertical position of the carriage, and particularly of the vertical member 51, may be adjusted to bring the plane of the cover parallel to that of the flanged locking ring 60 on the end of the press. 90

Mounted above and below the center of the press are supporting guides 61 and 62, which are adapted, as the press is withdrawn from engagement with the vulcanizer to engage against corresponding guides 63 and 64 mounted on the arm 51. The engagement of the members 61 and 63, and 62 and 64, serves to take the greater part of the load from the screw shaft 54 and to transfer this to these guides, thus rendering the operation of the screw shaft very much easier for the operator and preventing it from wearing unduly as would be the case were the entire weight of 100 the cover supported on this shaft. 110

In Fig. 8 I have shown a combined pressure and suction packing gland, which may be used with either of the two types of covers here shown, or in fact, with other covers if desired. This packing gland is in the form of a Y-shaped strip 70 provided with arms 71, 72 and 73. The arm 73 is received in a recess 74 in the flanged ring 75, which is mounted on the end of the press, and which carries the usual locking lugs 76. The arms 71 and 72 of the gland press against the face 77 of the cover 78, which is provided with the usual lugs 79 for engagement beneath the lugs 76. As these lugs are interengaged they force the 120 125 130

cover 78 against the ring 75, pressing the packing firmly against the inner surface 77 of the cover and against beveled surfaces 80 and 81 extending from the groove 74 in the 5 ring. The form of the packing gland with the two arms directed in opposite directions securely seals the cover to the ring against both pressure from within the press, and suction from within the press, as the case may be. 10 The particular advantages of the cover and the mounting therefor which are here shown are that they can be used in a restricted space where there is very little head room in front of the vulcanizer presses, as is often the case 15 in factories where these presses are employed. Furthermore, by mounting the covers on carriages they can be bodily moved out of the way when it is desired to charge or discharge the press, the same tracks serving for all of the presses, and all of the carriages on which 20 the heads or covers are mounted.

Other modes of applying the principle of my invention may be employed instead of the one explained, change being made as regards 25 the mechanism herein disclosed, provided the means stated by any of the following claims or the equivalent of such stated means be employed.

I therefore particularly point out and distinctly claim as my invention:—

1. In a vulcanizer, the combination with a horizontally disposed casing forming a vulcanizing chamber open at one end, a carriage movable transversely of said casing, a bracket 35 pivotally mounted on said carriage, and a cover supported on said bracket and movable into and out of registration with said casing.

2. In a vulcanizer, the combination with a horizontally disposed casing forming a vulcanizing chamber open at one end, a trackway 40 extending transversely of said casing, guide means mounted parallel to said trackway and above the same, a carriage movably supported on said trackway and having means engaging said guide means, and a 45 cover mounted on said carriage for movement toward and away from said casing.

3. In a vulcanizer, the combination with a horizontally disposed casing forming a vulcanizing chamber open at one end, a trackway 50 extending transversely of said casing, guide means mounted parallel to said trackway and above the same, a carriage movably supported on said trackway and having 55 means engaging said guide means, a supporting member pivotally mounted on said carriage, and a cover on said member movable into and out of engagement with said casing.

4. In a vulcanizer, the combination with a horizontally disposed casing forming a vulcanizing chamber open at one end, a trackway 60 extending transversely of said casing, guide means mounted parallel to said trackway and above the same, a carriage movably supported on said trackway and having 65

means engaging said guide means, and a cover mounted on said carriage for oscillation in both a horizontal and vertical plane.

5. In a vulcanizer, the combination with a horizontally disposed casing forming a vulcanizing chamber open at one end, a trackway 70 extending transversely of said casing, guide means mounted parallel to said trackway and above the same, a carriage movably supported on said trackway and having means engaging said guide means, a supporting member pivotally mounted on said carriage, a cover for said casing oscillatorily mounted on said supporting member, and means engaging said cover to lock the same 75 against oscillatory movement.

6. In a vulcanizer, the combination with a horizontally disposed casing forming a vulcanizing chamber open at one end, a trackway 80 extending transversely of said casing, guide means mounted parallel to said trackway and above the same, a carriage movably supported on said trackway and having means engaging said guide means, a supporting member pivotally mounted on said carriage, a cover for said casing oscillatorily mounted on said supporting member, and latch means on said cover, said means engaging said supporting member and locking said 85 cover against oscillatory movement. 90

7. In a vulcanizer, the combination with a horizontally disposed casing forming a vulcanizing chamber open at one end, a trackway 95 extending transversely of said casing, guide means mounted parallel to said trackway and above the same, a carriage movably supported on said trackway and having means engaging said guide means, a supporting member pivotally mounted on said carriage, means for adjusting the vertical position of said supporting member, and a cover on said member movable into and out of engagement with said casing. 100

8. In a vulcanizer, the combination with a horizontally disposed casing forming a vulcanizing chamber open at one end, a trackway 110 extending transversely of said casing, guide means mounted parallel to said trackway and above the same, a carriage movably supported on said trackway and having means engaging said guide means, a supporting member pivotally mounted on said carriage, means for adjusting the vertical position of said supporting member, a cover oscillatorily mounted on said supporting member about a 115 horizontal axis and movable slightly about a second horizontal axis at right angles to the plane of such first-named axis, and means maintaining said cover in a predetermined position with respect to said last-named axis. 120

9. In a vulcanizer, the combination with a horizontally disposed casing forming a vulcanizing chamber open at one end, of a carriage 125 movable transversely of said casing, a supporting bracket mounted on said car- 130

- riage, a cover for said casing oscillatorily mounted on said bracket, and means for independently adjusting the vertical position of both said bracket and said cover.
- 5 10. In a vulcanizer, the combination with a horizontally disposed casing forming a vulcanizing chamber open at one end, a carriage movable horizontally and in a substantially straight line transversely of said casing, a
- 10 15 cover for such open end of said casing, said cover being supported on said carriage, and means for advancing said cover in the plane of said casing into engagement therewith.
11. In a vulcanizer, the combination with a horizontally disposed casing forming a vulcanizing chamber open at one end, a carriage movable horizontally and in a substantially straight line transversely of said casing, a cover for such open end of said casing, means
- 20 for advancing said cover into engagement with said casing in position closing such open end, and other means supporting said cover during such movement.
12. In a vulcanizer, the combination with a horizontally disposed casing forming a vulcanizing chamber open at one end, a carriage movable horizontally and in a substantially straight line transversely of said casing, a cover for such open end of said casing, means for advancing said cover into engagement with said casing in position closing such open end, and other means supporting said cover during such movement, said means including arcuate interengaging members on said carriage and said cover, and said members permitting oscillation of said cover about a central axis.
- 25 30 35

Signed by me, this 6th day of March, 1924.

H. LLOYD WILLIAMS.
